[57] CLAIM

The ornamental design for a vehicle bumper, substantially as shown and described.

DESCRIPTION

FIG. 1 is a front elevational view of a vehicle bumper showing my new design;

FIG. 2 is a rear elevational view of FIG. 1;

FIG. 3 is an end elevational view of FIG. 1, the opposite end being a mirror image thereof;

FIG. 4 is a top plan view of FIG. 1;

FIG. 5 is a bottom plan view of FIG. 1;

FIG. 6 is a front elevational view of a vehicle bumper showing a second embodiment of my new design;

FIG. 7 is a rear elevational view of FIG. 6;

FIG. 8 is an end elevational view of FIG. 6, the opposite end being a mirror image thereof;

FIG. 9 is a top plan view of FIG. 6; and

FIG. 10 is a bottom plan view of FIG. 6.
